UNITED STATES PATENT OFFICE.

EDGAR C. MORAN, OF CHICAGO, ILLINOIS.

DESIGN FOR A LAMP-BODY.

SPECIFICATION forming part of Design No. 33,959, dated January 22, 1901.

Application filed December 29, 1900. Serial No. 41,542. Term of patent 7 years.

To all whom it may concern:

Be it known that I, EDGAR C. MORAN, a citizen of the United States, residing at Chicago, in the county of Cook and State of Illinois, have invented and produced a new and original Design for Lamp-Bodies, of which the following is a specification, reference being had to the drawing forming a part thereof.

The accompanying drawing is a side elevation of a lamp-body constructed according to my design.

As shown in the drawing, the leading or material features of my design lie in the configuration and ornamentation of a lamp-body.

The body portion A is oviform or, perhaps, more nearly of the form of a lemon. It has an equatorial raised band or bead A' and at its lower end has the downwardly-extending curving annular base-flange A². At the upper end the body portion A is provided with the stem A³, surrounded by concentric beads A⁴, formed in the body portion A.

From opposite sides of the body portion, about midway between the equator and the

upper pole, extend two outwardly-curving diverging arms A⁵ and A⁶. These arms are secured to the body portion A by the annular shoulders A⁷. The arms A⁵ and A⁶ curve outward and upward and at their upper ends turn inward to face each other. The arm A⁵ is considerably longer than the arm A⁶, its upper end extending horizontally for some distance. At its extremity it has the enlarged portion A⁸ and directly over the stem A³ bears a shield A⁹. An upwardly-curving scroll A¹⁰ in bale form is secured at one of its ends to the arm A⁵ and at its other end to the arm A⁶, and scrolls A¹¹ are secured to the arms A⁵ and A⁶ near their lower ends and extend between said arms and the body portion A of the lamp.

I claim as my invention—

The design for a lamp-body, substantially as herein shown and described.

EDGAR C. MORAN.
